FOLDING SUPPORT

Walter E. Mowrey, Glendale, Calif.

Application May 20, 1946, Serial No. 670,996

2 Claims. (Cl. 311—84)

1

This invention relates to a folding support and is particularly directed to folding means for supporting a sawhorse, table, bench, or the like.

The principal object of this invention is to provide a novel folding support for such an article or device having legs which are adapted in one position to lie adjacent the body of the device for compactness and to be pivotally extended to another position to provide a rigid support.

Another object is to provide novel brace means for pivotally mounted legs on a device of the type described.

Another object is to provide a novel form of latch means for maintaining the braces and legs in the fully extended position.

Another object is to provide an improved form of pivotal attachment for the folding legs of a table, bench, sawhorse or the like having maximum rigidity and ease of operation, together with light weight and compactness.

Other objects and advantages will appear hereinafter.

The present invention will be described in connection with its embodiment in a folding sawhorse, but it is to be understood that the invention has equal usefulness as applied to a table, bench, chair, desk, etc.

In the drawings:

Figure 1 is a side elevation of a folding sawhorse embodying my invention, with the legs in their fully retracted position.

Figure 2 is a bottom plan view.

Figure 3 is a fragmentary, detailed perspective view showing details of the trackway and sliding connection with one of the struts.

Figure 4 is an end view of the device shown in Figure 1 with the legs moved to their fully extended position, the lower ends of the legs being broken away.

Figure 5 is a partial longitudinal sectional view showing details of construction of the latching device for releasably holding the strut in operative position.

Figure 6 is a side elevation of the device on a small scale illustrating the legs in their fully extended position.

Referring to the drawings, the working platform 10 is carried on the base 11, which extends longitudinally thereof. At each end of the base 11 is secured brackets 12 which are provided with symmetrically disposed depending flanges 13 and 14.

As shown in Figures 2 and 4, the flanges 13 and 14 extend downwardly at an angle from the central portion of the bracket 12. The right angle extension 15, 16 is provided on the back side of each flange 14 for a purpose described below.

Pivotal elements, such as bolts 17 and 18, extend through the flanges 13 and 14 in a direction respectively normal thereto, and the upper ends of the legs 19 and 20 are carried on these bolts. The angular mounting of the flanges 13 and 14 is such that the legs 19 and 20 lie in parallel relation in their retracted position on the base 11, but upon being pivotally moved to their operative extended position, the free ends 21 and 22 of the legs 19 and 20 separate in a transverse direction. In their fully extended position they provide a wide footing for support of the sawhorse against overturning, as will be readily understood from a consideration of Figures 4 and 6. In their fully extended position, the legs 19 and 20 are engaged by the extensions 15 and 16, respectively, to contribute to the provision of a relatively rigid connection between the upper ends of the legs and the base 11.

Transverse apertures or openings 23 and 24 are provided through the legs 19 and 20, respectively, intermediate their ends. A transverse tie-rod 25 extends loosely through the apertures 23, 24, and is provided with nuts 26 and washers 27 on each end, which are adapted to contact the sides of the legs 19 and 20 in their fully extended position. This arrangement is shown in Figure 4.

A strut 28 is secured at one end to the tie-rod 25 by any convenient means, such as welding, and is curved at its other end to slide between a pair of juxtaposed longitudinally extending arms 29 and 30, which cooperate to form a trackway generally designated 31. Slots 32 and 33 may be formed on the sides of the strut 28 for sliding engagement with the arms 29 and 30.

Means are provided for releasably securing the strut 28 in a position corresponding to the fully extended position of the legs 19 and 20, and as shown in Figure 5, this means includes a transverse pin 34 extending between the elements 29 and 30 of the trackway 31, which is adapted to limit outward travel of the strut 28 along the trackway 31. A resilient stop element 35 is secured to the base 11 at a location between the track elements 29 and 30.

As the sliding end of the strut approaches the stop pin 34, the resilient stop element deflects to permit the strut to pass by, and when it reaches the pin 34 the stop element 35 springs inwardly to the position illustrated in Figure 5 to prevent return motion of the strut 28.

3

A release finger 36 is mounted on the strut 28 and is positioned for convenient manual actuation in order to deflect the resilient stop element 35 out of the path of the return travel of the strut 28; thus, when it is desired to move the legs back to their retracted position, the release finger 36 is actuated to deflect the resilient stop element 35 and thus permit sliding motion of the strut 28 relative to the trackway 31. A feature of this construction is that the resilient stop element 35 is mounted in a relatively inaccessible position between the rails 29 and 30 and the release finger 36 extends inwardly through the gap between the rails for actuation of the stop element 35. By this construction the stop element 35 is enclosed against accidental actuation and yet is readily movable by the finger 36.

The working platform 10 may be secured to the base 11 by any convenient means and it is contemplated that this platform may be reversible or replaceable whenever wear in service makes such action necessary or desirable. The platform 10 may advantageously be constructed of relatively thick plywood which may be inverted to present a new surface after the top side has become worn. The brackets 12 may be secured to the base 11 by means of the fastener elements 37. It will be understood that if desired the brackets 12 could be divided into two separate supporting elements, each having its flange for pivotally carrying its respective leg.

The longitudinal elements 29 and 30 forming the trackway 31 may be secured to the base 11 by fastener elements 38.

In order that the free ends of the legs in their retracted position may not interfere with the legs on the other end of the device, the brackets 12 may be displaced slightly on opposite sides of the longitudinal axis of the device, or they may be mounted at a slight angle to avoid such interference.

When the legs are moved to their fully extended position they provide a rigid support for the base 11 and working platform 10 since each leg is supported at its upper end by both the flanges 13, 14 and right angle extension 15, 16, as well as being maintained against further spreading movement by the washers 27 on the ends of the tie-rod 25. Furthermore, the co-operation of the strut 28 with the tie-rod 25 holds the legs against pivotal movement in either direction.

It is contemplated that the platform 10, base 11 and legs may be constructed of wood or of light gauge metal or of aluminum or magnesium alloy. Furthermore, it is apparent that certain of the parts, such as platform 10, base 11, trackway 31, etc., could be combined into a single integral unit without departing from the spirit of this invention.

Having fully described my invention, it is to

4

be understood that I do not wish to be limited to the details herein set forth, but my invention is of the full scope of the appended claims.

I claim:

- 5 1. A folding support for a device such as a table, bench, sawhorse, or the like, having in combination a platform, longitudinally spaced brackets fixed on the under side of the platform, transversely spaced pivotal supports on each bracket, the axes of said supports being symmetrically positioned at an angle to the platform, a pair of supporting legs on each bracket, one pivotally mounted on each support, means for moving both legs on either bracket simultaneously from an inoperative folded position to an operative extended position, said means including transverse tie-rod extending loosely through both legs at points intermediate the length of the legs, the length of the tie-rods being no greater than the width of the platform, and abutments on the ends of the tie-rods adapted to engage the legs in their fully extended position, one to act as a brace.
- 10 2. A folding support for a device such as a table, bench, sawhorse, or the like, having a platform, the combination of: a pair of brackets adapted to be fixed in spaced relationship to the underside of the platform, transversely spaced pivotal supports on each bracket, the supports extending at an angle symmetrically from each end of each bracket, a pair of supporting legs on each bracket, one pivotally mounted on each support, means for moving both legs on either bracket simultaneously from an inoperative folded position to an operative extended position, said means including transverse tie-rods associated with both legs at a point intermediate the length of the legs, abutments on the ends of the tie-rods adapted to engage the legs in their fully extended position only to act as a brace,
- 15 3. A folding support for a device such as a table, bench, sawhorse, or the like, having a platform, the combination of: a pair of brackets adapted to be fixed in spaced relationship to the underside of the platform, transversely spaced pivotal supports on each bracket, the supports extending at an angle symmetrically from each end of each bracket, a pair of supporting legs on each bracket, one pivotally mounted on each support, means for moving both legs on either bracket simultaneously from an inoperative folded position to an operative extended position, said means including transverse tie-rods associated with both legs at a point intermediate the length of the legs, abutments on the ends of the tie-rods adapted to engage the legs in their fully extended position only to act as a brace,
- 20 4. A folding support for a device such as a table, bench, sawhorse, or the like, having a platform, the combination of: a pair of brackets adapted to be fixed in spaced relationship to the underside of the platform, transversely spaced pivotal supports on each bracket, the supports extending at an angle symmetrically from each end of each bracket, a pair of supporting legs on each bracket, one pivotally mounted on each support, means for moving both legs on either bracket simultaneously from an inoperative folded position to an operative extended position, said means including transverse tie-rods associated with both legs at a point intermediate the length of the legs, abutments on the ends of the tie-rods adapted to engage the legs in their fully extended position only to act as a brace,
- 25 5. A folding support for a device such as a table, bench, sawhorse, or the like, having a platform, the combination of: a pair of brackets adapted to be fixed in spaced relationship to the underside of the platform, transversely spaced pivotal supports on each bracket, the supports extending at an angle symmetrically from each end of each bracket, a pair of supporting legs on each bracket, one pivotally mounted on each support, means for moving both legs on either bracket simultaneously from an inoperative folded position to an operative extended position, said means including transverse tie-rods associated with both legs at a point intermediate the length of the legs, abutments on the ends of the tie-rods adapted to engage the legs in their fully extended position only to act as a brace,
- 30 6. A folding support for a device such as a table, bench, sawhorse, or the like, having a platform, the combination of: a pair of brackets adapted to be fixed in spaced relationship to the underside of the platform, transversely spaced pivotal supports on each bracket, the supports extending at an angle symmetrically from each end of each bracket, a pair of supporting legs on each bracket, one pivotally mounted on each support, means for moving both legs on either bracket simultaneously from an inoperative folded position to an operative extended position, said means including transverse tie-rods associated with both legs at a point intermediate the length of the legs, abutments on the ends of the tie-rods adapted to engage the legs in their fully extended position only to act as a brace,
- 35 7. A folding support for a device such as a table, bench, sawhorse, or the like, having a platform, the combination of: a pair of brackets adapted to be fixed in spaced relationship to the underside of the platform, transversely spaced pivotal supports on each bracket, the supports extending at an angle symmetrically from each end of each bracket, a pair of supporting legs on each bracket, one pivotally mounted on each support, means for moving both legs on either bracket simultaneously from an inoperative folded position to an operative extended position, said means including transverse tie-rods associated with both legs at a point intermediate the length of the legs, abutments on the ends of the tie-rods adapted to engage the legs in their fully extended position only to act as a brace,
- 40 8. A folding support for a device such as a table, bench, sawhorse, or the like, having a platform, the combination of: a pair of brackets adapted to be fixed in spaced relationship to the underside of the platform, transversely spaced pivotal supports on each bracket, the supports extending at an angle symmetrically from each end of each bracket, a pair of supporting legs on each bracket, one pivotally mounted on each support, means for moving both legs on either bracket simultaneously from an inoperative folded position to an operative extended position, said means including transverse tie-rods associated with both legs at a point intermediate the length of the legs, abutments on the ends of the tie-rods adapted to engage the legs in their fully extended position only to act as a brace,
- 45 9. A folding support for a device such as a table, bench, sawhorse, or the like, having a platform, the combination of: a pair of brackets adapted to be fixed in spaced relationship to the underside of the platform, transversely spaced pivotal supports on each bracket, the supports extending at an angle symmetrically from each end of each bracket, a pair of supporting legs on each bracket, one pivotally mounted on each support, means for moving both legs on either bracket simultaneously from an inoperative folded position to an operative extended position, said means including transverse tie-rods associated with both legs at a point intermediate the length of the legs, abutments on the ends of the tie-rods adapted to engage the legs in their fully extended position only to act as a brace.
